UNITED STATES PATENT OFFICE

DANIEL WILLIAM RANTINE, OF BROOKLYN, NEW YORK

SOUND REPEATER FOR SOUND REPRODUCING MACHINES

Application filed August 24, 1928. Serial No. 301,315.

This invention relates to phonograph repeaters and more particularly to devices whereby an ordinary disc record may be repeatedly played without manual resetting.

One of the objects of the invention is to provide a mechanism having a pair of reproducers to operate alternately on the record face, their spacing being adjustable to suit the size of the record used.

A further feature is in the provision of means for oscillating the arms at the ends of the record grooves whereby full and perfect repetitions are obtained automatically, correctly and without appreciable interruption of sound.

Another aim is to produce a simple and inexpensive device susceptible of long continued use without deterioration and which requires no special skill or experience in its successful operation.

These advantageous objects are accomplished by the novel construction, combination and arrangement of parts as hereinafter described and illustrated in the accompanying drawings, forming a material part of this disclosure, and in which:

Figure 1 is a side elevational view of an embodiment of the invention, parts being in section as taken on line 1—1 of Fig. 2.

Figure 2 is a top plan view of the same illustrating its application.

Figure 3 is a horizontal sectional view taken in a plane indicated by the line 3—3 of Fig. 4.

Figure 4 is a partial longitudinal sectional view taken on line 4—4 of Figs. 2 and 3.

Figure 5 is a partial transverse sectional view taken on line 5—5 of Fig. 2.

Figure 6 is a sectional view taken on line 6—6 of Fig. 3.

A fragmentary portion of a conventional gramaphone cabinet, generally designated by the numeral 10, is shown in Figs. 1 and 2 as provided with a fixed cover 11 through

the center of which extends an upright spindle 12 driven by motor means as usual.

The spindle 12 has secured on its upper portion a circular table 14 on which the record discs 15 are centered by the end of the spindle and frictionally driven by the table,

all these elements being well known and in common use.

Secured to the cover 11 is a base plate 16 through which the spindle 12 passes, an offset extending portion of the plate providing a bearing for a vertical spindle 17 having an enlarged upper end or head 17', its shoulder resting on the plate and its lower end being journaled in the base 18' of a cylindrical casing 18 fixed on the lower side of the plate 16, the spindle being rotatably held but prevented from longitudinal movement by a collar 19 fixed on its extending end as seen in Figs. 1 and 5.

Mounted in a transverse opening in the head 17' of the spindle is an axle bar 20 its ends being rotatably engaged in diametrically opposed openings in a base ring 21 having a concentric annular groove 21' in its upper surface in which is engaged a correspondingly shaped annular ridge formed on the lower edge of a second similar ring 22, having a like recess in its upper edge, and mounted on the ring 22 in a corresponding manner is a third ring 24 and seated on it is a fourth and uppermost ring 25 provided with a convex cover 26.

A cross bar 27 is fixed at its ends to extend across the interior of the second ring 22, this bar having at its center the squared portion 30 and head of a clamp bolt 28 reaching through the cover 26, its extending threaded end being provided with a thumb nut 29 by which the rings 22, 24 and 25 may be rigidly clamped together.

It is to be noted that the rings 22—24—25 and cover 26 may rotate as a unit with the base ring 21, which is entirely supported and carried by the axle bar 20 to freely oscillate or tip sidewise therein, and that the bar 20 is carried by the spindle 17 which is free to rotate in either direction, thus providing a limited range of tilting and rotary movement for the unit.

Resting on the base plate 16 is a cylindrical shield 30 having an inreaching upper edge making loose contact with the base ring 21, covering the space between it and the base plate and permitting the ring to move freely in any direction.

The uppermost ring 25 has lateral openings 31 and the next adjacent lower ring 24 has similar openings 32 in their opposite sides, these openings admitting sound from hollow tone arms 33—34 rigidly connected to the rings 24—25 respectively on their outer surfaces to cover the openings therethrough.

The free ends of the tone arms are outward turned and have attached to them reproducers 35—36 carrying styli 37—38 adapted to traverse the face of the record disc 15 from edge to center, from opposite sides, the styli being set at proper angles and arranged to impinge on diaphragms carried by the reproducer heads as usual.

From the foregoing it will be seen that as one or the other of the styli are moved by the sound grooves of a rotating record, the sound will be transmitted through the reproducer 20 to which it is attached and thence through the tone arm to the space within the rings and eventually out from the casing 18 to any preferred type of amplifying horn attached to it, the plate 16 and casing base 25 18' being respectively apertured as at 16" and 18" for the sound to pass freely therethrough.

Fixed to pivot in the arms 33—34, near the axis 28, are studs 39—40 drilled and threaded 30 to receive an adjusting screw 41 provided with right and left hand threads and having a knurled head 42 by which it may be turned readily.

At the center of the screw, between its oppositely threaded portions, are collars 43 having between them a fork 44 fastened to the ring 22 and further held stationary by a screw 45 the point of which contacts with an angular bracket 46 fixed on the lower ring 21 above the shield 30, this bracket having a part engaging a recess in the extending end of the axle bar 20, retaining it in position, see Fig. 4.

In order to gage the distance between the reproducers in accordance with the size of the record being used a curved scale plate 47 is attached to one of the tone arms and to the other arm is secured a similar arcuate plate 48 provided with an index pointer 49 by which 50 the scale on the plate 47 may be read as the screw 41 is turned in adjusting the arms.

Fixed on the base ring 21, near its upper edge, opposite the bracket 46, is a hinge leaf 50 connected by a pintle to an upper leaf 51; 55 a bent flat spring 52 is interposed between the leaf 51 and an angle bracket 53 fixed on the ring 22, the ends of the spring being connected to the bracket and leaf by screws 54, the arrangement being such as to permit 60 the reproducers, tone arms and elements connected by the bolt 28 to swing upwardly on the hinge.

Also rigidly secured on the base ring 21, above the guard 30 and at a right angle with 65 the center line of the brackets 46—53, is an

angularly pointed oscillator arm 55 extending horizontally to one side outwardly between upper and lower spring switch arms 56—57, the latter being secured on an extension of the base plate 16 and the former, upper arm 70 held raised by a spacer stud 58 also set in the plate 16. (See Figures 3 and 5).

The spring arms are arcuately curved in plan, concentrically spaced from the ring 21, their free inner ends being bent towards each other into substantially the same horizontal plane, see Fig. 6, enclosing an open space therebetween.

On the laterally extending portion of the base plate 16 is secured a pair of spaced 80 guides 60—61 between which is guided a slide 62 movable radially with respect to the axis 17 and having at its raised inner end a rounded knob 63 adjustably engageable with the oscillator arm 55.

The guide 61 has a raised arcuate edge 64 provided with a scale 65 which indicates the arc length of the stylus movement and is traversable by a pointer lever 66 pivoted on a pin 67 set in a projection 62' of the slide 90 and extending through a slot 68 in the pointer body, which is actuated by a knob 69 set therein.

The opposite end of the lever 66 has passing through it a bolt 70 having a clamp nut 71 to hold the lever in an adjusted position, a slot 72 in the slide 62 permitting movement of the slide relative to the bolt which passes therethrough and acts as the pivot for the lever 66.

In operation, the styli are set to the right distance apart for the size of the record by slackening the clamp bolt nut 29, adjusting the screw 41 until the pointer and scale indicate the correct distance and then re-clamping the elements firmly together. In order to conveniently and correctly set the arms to a record the distance between the styli of the two reproducers should be known and also the length of the sweep or movement of the 105 styli over the face of the record.

These distances may preferably be determined from a printed label covering the central portion of the record.

The styli are raised and lowered relative 115 to the record groove by the adjusting screw 45, causing the upper rings to move on the hinge 50—51, the spring 52 taking up any slight inequalities.

When the sweep or stroke of the styli is 120 known the timer slide 62 is adjusted by the index lever 66 to the scale 65 and then clamped by the bolt 70, the knob 62 co-acting with the oscillator arm 55 which moves over it, tilting the united rings, arms and reproducers and causing the stylus 37 to contact the disc 15, simultaneously raising the stylus 125 38 therefrom.

As the stylus 37 moves over the record disc 130 towards its center, the arm 55 passes over

the knob 63, which may be adjusted to engage its point or further in along its constantly increasing width, the arm upon passing off the knob being moved downwardly by the 5 spring arm 56, tilting the ring unit and its associated parts on the axle bar 20 and bringing the stylus 38 into position for operation.

Obviously the positions of the styli are reversed at each passage across the face of the 10 disc, the oscillating arm moving in a circular path around the knob 63, which may be adjusted to tilt the ring unit at any point along the face of the disc as may be desired.

The foregoing disclosure is to be regarded 15 as descriptive and illustrative only, and not as restrictive or limitative of the invention, of which obviously an embodiment may be constructed including many modifications without departing from the general scope 20 herein indicated and denoted in the appended claims.

Having thus described the invention, what is claimed as new and desired to secure by Letters Patent, is:—

25 1. In a repeater for graphophones using disc records, a plurality of superposed rings having interengaging edges, a cover thereover, bolt to clamp said rings and cover said rings and cover constituting a sound chamber, and a pair of reproducer carrying arms carried respectively by the two upper rings said arms being hollow and open to said chamber.

30 2. In a repeater for graphophones using disc records, a plurality of superposed rings having interengaging edges, a pair of tone arms fixed in open communication with two adjacent rings and carrying reproducers at their outer ends, means for adjusting the angular distance between said arms, an indicator having a scale to show such distance, and means for clamping the arm carrying rings when adjusted.

35 3. In a repeater for graphophones using disc records, a plurality of superposed rings having interengaging edges, a base ring therebelow, a horizontal spindle passing diametrically through the base ring, a rotatably mounted vertical shaft having a head 40 in which said spindle is mounted, reproducer carrying arms attached to two adjacent upper rings, and a single means to clamp all of said rings except the base ring when said arms are in adjustment.

45 4. In a repeater for graphophones using disc records, a plurality of superposed rings having interengaging edges, a hinge connecting the base ring and next adjacent ring, means for clamping all of said rings except 50 the base ring, a spring interposed over said hinge and adjacent ring, and means for adjusting said clamped rings relative to the base ring.

55 5. In a repeater for graphophones using disc records, a plurality of superposed rings

having interengaging edges, a base ring therebelow, an oscillator arm fixed on said base ring, a base plate, means on said plate to oscillatably and rotatably support said base ring, and other means on said base plate 70 adjustably contactable with said arm to control the oscillations of said rings relative to their rotary movement.

6. In a repeater for graphophones using disc records, a base plate attached to the graphophone, an upright shaft journalled therein, a horizontal spindle journalled in the upper end of said shaft, a base ring pivotally carried by said spindle, a series of rings 75 interengaged at their edges with each other and with said base ring, reproducer arms carried by two adjacent rings, of the series means for clamping all the rings of said series, and a guard ring mounted on said base plate circumjacent said base ring.

80 7. A repeater for sound reproducing machines using a flat record disc, comprising a base plate fixed to extend from the machine, a laterally rockable and axially rotatable base ring mounted on said plates, a series of rings 85 interengaged at their edges, a cover thereover, means for clamping said series of rings as a unit, hinge connections between said base ring and unit, a pair of opposed reproducer carrying arms attached to two adjacent relatively rotatable rings of said series, said reproducers having styli to engage the grooves of a record, means for adjusting the distance apart of said reproducers, means for raising and lowering the styli upon said hinge, and means for rocking said rings and associated parts in timed alternate relation.

90 8. A repeater for sound reproducing machines using a flat record disc, comprising a base plate fixed to extend from the machine, a laterally rockable and axially rotatable base ring mounted on said plates, a series of rings 95 interengaged at their edges, a cover thereover, means for clamping said rings as a unit, tone arms communicatively attached to two rings in said series, said arms having opposed reproducers at their ends provided with styli to engage the record from opposite sides of its face, means to adjust the angular distance apart of said arms relative to the axis of said unit, and a scale by which the distances apart of the arms may be determined.

100 9. A repeater for sound reproducing machines using a flat record disc, comprising a base plate fixed to extend from the machine, a laterally rockable and axially rotatable base ring mounted on said plates, a series of rings 105 interengaged at their edges, a cover thereover, means for clamping said rings as a unit, tone arms communicatively attached to two rings in said series, said arms having opposed reproducers at their ends provided with styli to engage the record from opposite sides of its face, and means to tilt all of said 110

rings and associated parts alternately in opposite lateral directions whereby the styli are alternately brought into operative relation with the record.

10. A repeater for sound reproducing machines using a flat record disc, comprising a base plate fixed to extend from the machine, a laterally rockable and axially rotatable base ring mounted on said plate, a series of rings interengaged at their edges, a cover thereover, means for clamping said rings as a unit, tone arms communicatively attached to two upper rings in said series, said arms having opposed reproducers at their ends provided with styli to engage the record from opposite sides of its face, means to automatically tilt said arms and associate parts to bring said styli alternately into contact with the record, and means to adjustably vary the periodicity of such alternations.

11. A repeater for sound reproducing machines using a flat record disc, comprising a base plate fixed to extend from the machine, a hollow cylinder mounted to rotate axially thereon, said cylinders being composed of a plurality of sections, means to tilt said cylinder limitedly sidewise, a tone arm carried by the uppermost section, a second tone arm carried on the opposite side of the next adjacent section, said arms being provided with styli carrying reproducers adapted to alternately engage the record, means to adjust the contact between the styli and record, said means permitting the arms to be raised upright, means for adjustably spacing said arms, and means to control the time between tilting the cylinder and attached parts from one position to another.

12. A repeater for sound reproducing machines using a flat record disc, comprising a base-plate fixed to extend from the machine, a sectional hollow cylinder mounted to rotate and tilt on its axis thereon, means to tilt said cylinder limitedly sidewise, an oscillating arm fixed on the base-ring of said cylinder, a slidible timer-plate carried on the extending base-plate to coact with the oscillating arm of the cylinder, a pointed lever fixed to move said timer plate, and a scale on which the end-wise movement of said timer is indicated by said lever.

In testimony whereof I have signed my name to this application.

DANIEL WM. RANTINE.
